UNITED STATES PATENT OFFICE.

MILTON AUSTON SMITH, OF PORT HURON, MICHIGAN.

CARPET-STRETCHER.

No. 910,595.

Specification of Letters Patent.

Patented Jan. 26, 1909.

Application filed April 30, 1908. Serial No. 430,107.

To all whom it may concern:

Be it known that I, MILTON AUSTON SMITH, a citizen of the United States, residing at Port Huron, in the county of St. Clair and 5 State of Michigan, have invented a new and useful Carpet-Stretcher, of which the following is a specification.

The invention relates to improvements in carpet stretchers.

10 The object of the present invention is to improve the construction of carpet stretchers, and to provide a simple and inexpensive carpet stretcher, adapted to be easily and quickly operated, and capable of successively 15 stretching a carpet in any direction and of holding the carpet at the end of each stretching operation and while it is being arranged for the next stretching operation.

A further object of the invention is to provide 20 a carpet stretcher of this character, adapted to be advanced as the carpet is stretched, and capable, after a carpet has been sufficiently stretched, of holding the same with the slack at the edge, whereby the 25 carpet may be tacked with greater facility.

With these and other objects in view, the invention consists in the construction and 30 novel combination of parts hereinafter fully described, illustrated in the accompanying drawing, and pointed out in the claims hereunto appended; it being understood that various changes in the form, proportion, size and minor details of construction, within the 35 scope of the claims, may be resorted to without departing from the spirit or sacrificing any of the advantages of the invention.

In the drawing:—Figure 1 is a perspective view of a carpet stretcher, constructed in accordance with this invention and arranged 40 for operation. Fig. 2 is a side elevation, the front floor engaging member being reversed for firmly holding the device while a carpet is being tacked. Fig. 3 is an enlarged detail sectional view, illustrating the construction 45 of the catch for locking the front floor engaging member at the front of the carpet stretcher. Fig. 4 is a horizontal sectional view, illustrating the construction of the carpet engaging means. Fig. 5 is a rear elevation of the foot of the lever, the rear floor engaging device being in section.

Like numerals of reference designate corresponding parts in all the figures of the drawing.

55 1 designates a carpet stretching lever, provided at its lower end with a foot 2, to which

is secured a carpet engaging jaw 3, provided at its lower edge with teeth 4, arranged at intervals, as clearly illustrated in Fig. 1 of the drawing. The jaw, which is arranged on the front face of the foot 2, is secured to the same by bolts 5, piercing the jaw and the foot. The foot extends laterally from opposite sides of the lower end of the lever 1, and it is provided at its upper edge with forwardly projecting lugs 6, forming shoulders for engaging the upper edge of the jaw 3. The shoulders support or brace the jaw and relieve the bolts 5 of strain. The foot is provided at its lower edge with a central slot or opening 7, and it has bearing recesses 8, located at its inner or front face at opposite sides of the slot or opening to receive laterally extending pivots 9 of a rear floor engaging member 10. The floor engaging member 75 10 to which the foot 2 is hinged by the pivots 9, is provided with a forked rear or outer portion 11, having diverging sides, and provided with depending terminal prongs 12 adapted to be embedded in the floor for holding a carpet after one stretching operation and while the carpet stretcher is being arranged for again stretching the carpet. The sides of the forked portion 11 diverge rearwardly, and the prongs 12 are preferably formed by 80 bending the terminals of the sides of the fork downward. The carpet stretching lever is also connected with a front floor engaging member 13, consisting of a rod provided at its front end with a depending floor engaging 85 prong 14, and having its rear end bifurcated to form a pair of ears 15, which are pivoted by a pin or bolt 16 to an ear or lug 17 of a collar or sleeve 18. The collar or sleeve 18 is arranged on the lever 1 and is mounted for 90 rotary movement to enable the front floor engaging member to be reversed and changed from its position in advance of the lever 1, as shown in Fig. 1 of the drawing, to a position in rear of the lever, as illustrated in Fig. 100 2 of the drawing. The stretching lever is round and forms a pivot on which the collar 18 is adapted to turn, and it is provided with a supporting shoulder 19, located below the collar. The recessed collar 18 is arranged 105 between the lower shoulder 19, and an upper fixed collar 20, and is thereby held against upward or downward movement on the lever. The lower shoulder may, as illustrated in Fig. 3 of the drawing, consist of a 110 collar or band secured to the lever 1. The loose collar 18 is provided at its inner edge

with a recess 21, which is engaged by a lug or tooth 22 of a slidable catch 23. The lug or tooth extends through the upper fixed collar 20 and is held against lateral or rotary movement along the lever 1, whereby it is adapted to lock the front floor engaging member 13 in advance of the lever 1. This will prevent the front floor engaging member from shifting laterally.

10 The slidable catch is composed of upper and lower arms 24 and 25, spaced apart and connected by a front body portion. The lower arm 25 is engaged by a coiled spring 26, disposed on the lever and interposed between the lower arm 25 and a pin 27, piercing the lever 1 and forming an upper stop or bearing for the coiled spring. The slidable catch is provided at the front with a projecting lug or portion 28, tapered outwardly 20 and having its outer end beveled at its lower face. When the front member is swung upwardly it engages the outer end of the lug 28 at the lower face thereof and lifts the lug and operates the catch to carry the tooth 22 out 25 of engagement with the recess 21, and the tapering and beveling of the lug serves to automatically swing the front member laterally for carrying the said recess 21 beyond and out of alignment with the tooth 22 and 30 to assist in the reversal of the front member.

To stretch a carpet the point or prong of the front floor engaging member is embedded in the floor, and the lever 1 is inclined in the opposite direction from that shown in Fig. 1 35 to engage the jaw 3 with the carpet, which is stretched by moving the lever backward to the position shown in Fig. 1. The rear floor engaging member is then embedded in the floor to hold the carpet while the upper portion of the lever 1 is being swung forward to 40 advance the front floor engaging member, which is connected to the lever 1 at a point above the rear floor engaging member. After the front member 13 is reengaged with 45 the floor, the rear member 10 is disengaged from the floor and the lever 1 is again swung backward to stretch the carpet. This movement of the carpet stretcher advances the same across the floor, and after a carpet has 50 been stretched to the desired extent, the front engaging member is reversed and swung backward to a point in rear of the lever 1 and is embedded in the floor. This will hold the lever of the carpet stretcher firm and steady 55 and will leave the slack of the carpet in front of the carpet stretcher. This will enable the carpet to be readily tacked to the floor.

Having thus fully described my invention, what I claim as new and desire to secure by 60 Letters Patent, is:—

1. A carpet stretcher comprising a stretching lever provided at its lower end with carpet engaging means, a rear floor engaging member pivotally connected with and extending rearwardly from the lever, and a

front floor engaging member pivotally connected with the lever and extended in advance of the same.

2. A carpet stretcher comprising a stretching lever provided at its lower end with carpet engaging means, a rear floor engaging member pivotally connected with and extending rearwardly from the lever, and a front floor engaging member pivotally connected with the lever and extended in advance of the same, said front member being reversible to arrange it in rear of the lever at the completion of the stretching operation.

3. A carpet stretcher comprising a stretching lever provided at its lower end with carpet engaging means, a rear floor engaging member pivotally connected with and extending rearwardly from the lever, a front floor engaging member pivotally connected with the lever and extended in advance of the same, said front member being reversible to arrange it in rear of the lever at the completion of the stretching operation, and means for detachably locking the front floor engaging member in advance of the lever.

4. A carpet stretcher including a lever provided at its lower end with carpet-engaging means, and front and rear floor-engaging members pivotally connected with the lever at different distances from the carpet-engaging means.

5. A carpet stretcher including a lever provided at its lower end with a foot having an upper shoulder, a toothed carpet engaging jaw secured to the foot of the lever and fitted against the said shoulder, and front and rear floor engaging members pivotally connected with the lever.

6. A carpet stretcher including a lever provided at its lower end with a foot having an opening and provided at opposite sides thereof with bearing recesses, a rear floor engaging member extending through the opening of the foot and having pivots fitting in the said bearing recesses, a jaw secured to the foot and retaining the pivots in the recesses, and a front floor engaging member connected with the lever.

7. A carpet stretcher including a lever, front and rear members pivotally connected with the lever, the front member being reversible to arrange it in rear of the lever, and a catch located above the front member for locking the same in front of the lever, said catch being arranged to be operated by the front member to release the same.

8. A carpet stretcher including a lever, front and rear members pivotally connected with the lever, the front member being reversible to arrange it in rear of the lever, and a catch located above the front member for locking the same in front of the lever, said catch being arranged to be operated by the front member to release the same and having means for automatically swinging

the front member laterally while it is being operated.

9. A carpet stretcher including a lever, a rear floor engaging member connected with the lever, a front floor engaging member having a collar fitted on the lever and capable of rotary movement to arrange the front floor engaging member either in advance or in rear of the lever, and a catch mounted on the lever and engaging the collar for locking the same against rotary movement, said catch being arranged to be operated by the front member to release the collar.

10. A carpet stretcher including a lever, a collar mounted on the lever for rotary movement, a floor engaging member pivotally connected to the collar, a catch slideable on the lever and engaging the collar and arranged to be operated by the front member for releasing the collar, and a spring for holding the catch in engagement with the collar.

11. A carpet stretcher including a lever, a collar mounted on the lever for rotary movement and provided with a recess, a floor engaging member pivotally connected to the collar, a catch provided with a tooth for engaging the recess of the collar and having spaced arms slideable on the lever, and a spring mounted on the lever between the arms of the catch for holding the tooth in engagement with the collar, said catch being located above and arranged to be operated by the floor engaging member.

12. A carpet stretcher including a lever, upper and lower fixed collars, a loose collar arranged between the fixed collars, a catch provided with arms spaced apart and slideable on the lever, said catch being provided with a tooth for engaging the loose collar and

having a projecting portion, a spring for holding the tooth in engagement with the loose collar, and a floor engaging member connected with the latter and arranged to engage the projecting portion of the catch to operate the same for releasing the loose collar.

13. A carpet stretcher including a lever, a rear floor engaging member connected with the lever, a front floor engaging member having a collar fitted on the lever and capable of rotary movement to arrange the front floor engaging member either in advance or in rear of the lever, and a catch mounted on the lever for engaging the collar and having a tapered lug arranged to be engaged by the front member for releasing the collar and adapted to automatically swing the front member laterally to assist in the reversal of the same.

14. A carpet stretcher including a lever, a collar mounted on the lever for rotary movement and provided with a recess, a catch movably mounted on the lever and provided with a tooth for engaging the recess of the collar and having a tapered lug, and a floor engaging member pivoted to the collar and arranged to engage the tapered lug to operate the catch to release the collar, said floor engaging member being automatically swung laterally by the tapered lug while operating the catch, whereby the recess of the collar is carried out of alignment with the tooth of the catch.

In testimony, that I claim the foregoing as my own, I have hereto affixed my signature in the presence of two witnesses.
